UNITED STATES PATENT OFFICE.

JAMES M. SEYMOUR, JR., OF NEWARK, NEW JERSEY.

FIRE-ALARM OR SIGNALING SYSTEM.

1,208,389.

Specification of Letters Patent. Patented Dec. 12, 1916.

Application filed December 6, 1915. Serial No. 65,402.

To all whom it may concern:

Be it known that I, JAMES M. SEYMOUR, Jr., a citizen of the United States, residing at Newark, in the county of Essex and State of New Jersey, have invented certain new and useful Improvements in Fire-Alarm or Signaling Systems; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in alarm-system; and, the invention has reference, more particularly, to a novel fire-alarm system comprising in general a container or receptacle adapted to contain a fluid, as air, under compression, a line or lines of piping connected therewith and provided with an alarm signal or signals, a second line or lines of piping connected with said other line or lines of piping serving as a control and being fitted with valves, or the like, any one or more of which are adapted to be suitably operated, either manually or otherwise, all in combination with a diaphragm control.

The present invention has for its principal object to provide a simply-constructed and effectively operating fire-alarm system of the general construction and character hereinafter more fully set forth, and especially a system using in connection therewith a differentially operated diaphragm control.

The invention has for its further objects to provide a fire-alarm control or system, for alarm purposes in which the cost of maintenance has been reduced to a minimum; and to produce an efficiently operating system and one which can be depended upon to be at all times operative and certain in sounding an alarm under all conditions.

The invention has for its further objects to produce an alarm system of greatly reduced cost, both as to construction; to provide an alarm system giving dependability or a certainty of an alarm being given, when the system and apparatus may not be used for years; to provide a system and apparatus in which the depreciation of the material employed in the construction of the

system and apparatus does not endanger, during the life of the system and apparatus, the efficiency and dependability of the system; and finally, to provide an alarm system and apparatus which is always on the safe side, in that any disorder in the system or apparatus, due to a reduction or loss of the fluid-pressure, the breaking of a control line, or the leaking of a diaphragm will immediately sound an alarm or fire signal.

Other objects of the present invention not at this time more particularly enumerated will be clearly understood from the following detailed description of the present invention.

With the various objects of the present invention in view, the said invention consists, primarily, in the novel fire alarm or signaling system hereinafter set forth; and, the present invention consists, furthermore, in the several novel arrangements and combinations of the several devices and parts, as well as in the details of the construction of the said parts, all of which will be more fully described in the following specification and then finally embodied in the clauses of the claims which are appended to and which form an essential part of the said specification.

The invention is illustrated in the accompanying drawings, in which—

Figures 1 and 2 represent, diagrammatically, one embodiment of the present invention, said Fig. 2 being a continuation of Fig. 1, on line *a*—*a* in said Fig. 1. Fig. 3 is a detail sectional representation, on an enlarged scale, of the diaphragm-damper regulator, and pipe-connections thereof.

Referring now to the said figures of the drawings, the reference-character 1 indicates the floor lines of a building, 2 the usual beams upon which the floors 1 are supported, and 3 indicates a foundation, usually the cellar line of the building, as a factory, public building, etc.

The reference-character 4 indicates a suitable reservoir or tank, adapted to contain a fluid, as air, under compression, the fluid within said reservoir or tank being brought under compression, to the degree of pressure desired, by a suitable pump, as 5, or other suitable mechanism, which is suitably connected with the said reservoir or tank 4 by means of a system of piping, as 6, connected with a four-way fitting 7, from which extends a piece of pipe 8 which communi-

cates with the said reservoir or tank, as at 9. Suitably located in the line of piping 6 may be a check-valve 10 of any suitable construction, a shut-off valve 11, and a pressure-indicating gage 12.

If desired, there may be connected with the reservoir or tank 4, as at 13, a line of piping 14 leading to and connected with a pressure-source, as a steam boiler or the like, 10 the same however not being shown in the accompanying drawings.

To maintain the pressure within the said reservoir or tank 4, under normal conditions, at a greater degree than that of the pressure-source with which the piping 14 is connected, a suitable check-valve 15, or the like, is mounted in the piping 14, the valve-plate or disk 16 of which always remains in its closed relation upon the seat of the valve, 20 as long as the pressure of the fluid within the reservoir or tank 4 is greater than that of the said pressure-producing source in the piping 14, as will be clearly evident.

Connected with and leading from the 25 four-way fitting 7 is a pipe 17 having connected thereto a T-fitting, as 18, and connected with and leading from this fitting 18 is a line of piping, as 19, which extends upwardly through the various floors of the 30 building, and is suitably closed, as at 20, by means of a cap 21, or otherwise. Suitably mounted in this pipe 19, upon the several floors of the building, are suitable fittings, as 22, with which are connected pipes, 35 as 23, each pipe having an end 24, which may be opened to the air, as will be presently more fully set forth. In each pipe 23 is suitably mounted a normally closed shut-off valve, as 25, each valve having an operating 40 handle or lever 26, and an operating chain 27 or the like, for manually operating the valve or valves, as will be clearly understood. Of course, it will be evident, that any other suitable means for operating said 45 valves, manually or otherwise, may be employed. Extending in an upward direction from the previously mentioned T-fitting 18 is a pipe 28, upon which is mounted and with which is connected, so as to establish 50 communication therewith, a suitably constructed diaphragm damper-regulator, as 29.

Within the pipe 17, at a point in front of the fitting 18, the cross-area of the said pipe 17 is suitably reduced by the insertion in 55 said pipe of a plug 30, having a small hole or duct 31, Fig. 3 of the drawings; but, it will be understood, that any other means for so reducing the area may be employed, if desired. The purpose of this is, under 60 normal conditions, to keep the diaphragm inflated, or to maintain the static pressure through said reduced opening with the pressure maintained in the reservoir or tank 4, and the said reduced opening, under other 65 conditions, on account of the larger release

opening to said diaphragm, allowing the air to escape from said diaphragm, in the manner and for the purposes to be herein-after more fully described. Suitably mounted upon the said reservoir or tank 4, 70 or secured in any other suitable position, is a support, as 32, upon which is pivotally mounted, as at 33, a suitable bell-crank or device comprising two arms, as 34 and 35. The arm 34 rests upon a knife-edge, or other 75 suitable supporting means, as 36, carried by said diaphragm, and adjustably arranged upon said arm 34 is a slide or weight, as 37, for maintaining the carrying engagement between said arm 34 and the said supporting means 36, as will be evident. The said arm 35 carries upon it upper end, or in any other suitable portion, a holding member or nosing, as 38.

Connected with and extending upwardly 80 from the previously mentioned four-way fitting 7 is a line of piping 39, leading to the several floors of the building, and being closed at its upper end by means of a suitable cap, as 40, or otherwise. Mounted in 90 said pipe, upon each floor of the building, are suitable fittings, as 41, with which are suitably connected suitable whistles, as 42, or other suitably constructed alarm or signal-giving devices. Suitably mounted, in the proper location, in said pipe 39 is a normally 95 closed shut-off valve 43 adapted to be supported by means of a lever 44 carrying a weight 45. The position of this lever 44, indicated in Fig. 1 of the drawings, is maintained by a flexible connection, as 46, which passes over a pulley or pulleys, as 47, and has attached to its other end a member, as 48, provided with a projection, as 49, held in engagement with the holding member or nosing 38 of the bell-crank arm 35. When the holding or retaining engagement between the said nosing 38 and the projection 49 is broken, by the collapsing of the diaphragm-members, in the manner hereinafter 100 described, a suitable spring-device, as 50, suitably attached to the support 32, helps to further force the member 48 away from the nosing of the arm 35, thus allowing the weight 45 to operate the lever 44, and thereby 105 open the valve 43.

Having in the foregoing described the general arrangements and constructions of the several devices comprising the novel alarm or signaling system, I will now briefly 110 describe the operation thereof.

Under normal conditions, by means of the pump or compressor 5, the fluid within the reservoir or tank 4 is suitably brought under compression, to the degree of pressure desired, some of the fluid at the same time passing through the pipes 17 and 18 into the diaphragm damper-regulator 29, the several valves 25 in the pipe 19 and the valve 43 in the pipe 39 being closed, whereby the said 115 120 125 130

diaphragm device 29 becomes sufficiently inflated, substantially as shown in Figs. 1 and 3 of the drawings. At the same time, the arm 34 is raised into the position indicated, and the member or element 48 is brought into retained engagement with the nosing 38 of the arm 35, as shown. The result is, as will be clearly evident, that the shut-off valve 43 in the pipe 39 will be maintained in its closed relation to said pipe and the whistles or signaling devices 42 therein. When it is desired to give a signal or to blow an alarm on all floors of the building, as in case of a fire, any one of the flexible members or chains 27 is pulled in a downward direction, whereby the respective valve 25 is opened. The consequent result is that the fluid within the diaphragm device 29 can now escape through the pipe 19 and to the opened pipe 23 at its open outlet-end 24, on account of the fact that the combined weight of the arm 34 and its weight 37 causes the diaphragm-member to collapse. At the same time, the position of the bell-crank disengages the nosing 38 of the arm 35 from the projection 49 of the member or element 48, thereby permitting the weight 45 to pull the lever 44 in a downward direction so as to open the valve 43 in the pipe 39. The reduced area of the opening in the plug 30 located within the pipe 17, prevents a too free escape of the compressed fluid within the reservoir or tank 4 from the latter through the pipe 17, but its free passage into and through the pipe 39 and the opened valve 43 therein, permits the said fluid to escape from all the whistles 42, thus positively blowing an alarm upon all floors of the building. When the reservoir or tank 4 is connected by means of the pipe 14 and check valve 15 with a steam boiler, or other pressure-producing source, as soon as the pressure within the reservoir or tank falls below that of the steam-boiler or other pressure-producing source, then the pressure back of the check-valve 15 lifts the said check-disk 16 off its seat, so that a constant pressure will be maintained through the pipe 14, the reservoir or tank 4, and the pipes 8 and 39, thereby still continuing to sound the alarm at the whistles 42, as will be clearly evident. This connection of the reservoir or tank 4 with a steam boiler or pressure-producing source also has this further advantage that in case of any disorder in the apparatus, such as a loss of air pressure for any cause, or due to breaking of a control line, leaking of a diaphragm, or other cause, will be immediately detected, for such cause will open the valve 43 in the pipe 39, and the alarm or signal will immediately be given. From the foregoing description of my present invention it will be clearly seen that I have devised a simply constructed and effectively operating alarm-signal which will not readily get out of order, and a system is produced that does not require delicate adjustments, such as are required with electrically operated or controlled fire alarm systems, and a more dependable system and apparatus is therefore one of the results of my present invention.

Of course I am aware that various other means may be employed, operated manually or otherwise, for controlling the fluid, whether air, gas, or steam, into and through the lines of pipes 19 and 39, and other means for operating the valves may be employed.

I am also fully aware that changes may be made in the general arrangements and combinations of the various devices and parts, as well as in the details of the constructions of the said parts, without departing from the scope of the present invention as set forth in the foregoing specification. Hence, I do not limit my present invention to the exact arrangements and combinations of the devices and parts as described in the accompanying specification, nor do I confine myself to the exact details of the construction of the said parts as illustrated in the accompanying drawings.

I claim:

1. A fire or signaling alarm comprising a main line of piping and a pair of auxiliary lines of piping connected with and extending from said main line of piping, means for conducting a pressure-exerting fluid into said main line of piping, one of said auxiliary lines being fitted with a fluid-operated signal and means for actuating said signal, a normally inflated diaphragm control connected with and located in said main line of piping intermediate of said pair of auxiliary lines of piping, the diaphragm of said control being subject to pressure only upon one side thereof, and upon its other side supporting said signal-actuating means, and means in the other auxiliary line of piping for deflating said diaphragm-control and releasing said signal-actuating means to admit the fluid into and through said fluid-operated signal.
2. A fire or signaling alarm comprising a main line of piping and a pair of auxiliary lines of piping connected with and extending from said main line of piping, means for conducting a pressure-exerting fluid into said main line of piping, one of said auxiliary lines being fitted with a fluid-operated signal and means for actuating said signal, a normally inflated diaphragm-control connected with and located in said main line of piping intermediate of said pair of auxiliary lines of piping, the diaphragm of said control being subject to pressure only upon one side thereof, and upon its other side supporting said signal-actuating means, a normally closed valve in the other auxiliary line of piping, and means for operating and

opening said valve for deflating said diaphragm-control and releasing said valve-actuating means to admit the fluid into and through said fluid-operated signal.

5. 3. A fire or signaling alarm comprising a main line of piping and a pair of auxiliary lines of piping connected with and extending from said main line of piping, means for conducting a pressure-exerting fluid into 10 said main line of piping, one of said auxiliary lines of piping being fitted with a fluid-operated signal, a normally closed valve in said line of piping, and means for actuating said valve, a normally inflated 15 diaphragm-control connected with and located in said main line of piping intermediate of said pair of auxiliary lines of piping, the diaphragm of said control being subject to pressure only upon one side thereof 20 and upon the other side supporting said valve-actuating means and means in the other auxiliary line of piping for deflating said diaphragm-control and releasing said valve-actuating means to admit fluid into 25 and through said fluid-operated signal.

4. A fire or signaling alarm comprising a main line of piping and a pair of auxiliary lines of piping connected with and extending from said main line of piping, 30 means for conducting a pressure-exerting fluid into said main line of piping, one of said auxiliary lines of piping being fitted with a fluid-operated signal, a normally closed valve in said line of piping, and means for actuating said valve, a normally inflated 35 diaphragm-control connected with and located in said main line of piping intermediate of said pairs of auxiliary lines of piping, the diaphragm of said control being subject to pressure only upon one side thereof 40 and upon the other side supporting said valve-actuating means, a normally closed valve in the other auxiliary line of piping, and means for operating and opening said 45 last-mentioned valve for deflating said diaphragm-control and releasing said valve-actuating means to admit fluid into and through said fluid-operated signal.

5. A fire or signaling alarm comprising a 50 reservoir or tank, adapted to receive a fluid, a fluid-compressor, a main line of piping leading from said compressor to said reservoir or tank, a pair of auxiliary lines of piping connected with and extending from said 55 main line of piping, one of said pair of auxiliary lines of piping being fitted with a fluid-operated signal, a normally closed valve in said line of piping, means for actuating said valve, a normally inflated diaphragm-control connected with and located in said main line of piping intermediate of 60 said pairs of auxiliary lines of piping, the diaphragm of said control being subject to pressure only upon one side thereof, and upon its other side supporting said valve- 65

actuating means, and means in the other auxiliary line of piping for deflating said diaphragm-control and releasing said valve-actuating means to admit fluid into and through said fluid-operated signal.

6. A fire or signaling alarm comprising a 70 reservoir or tank, adapted to receive a fluid, a fluid-compressor, a main line of piping leading from said compressor to said reservoir or tank, a pair of auxiliary lines of 75 piping connected with and extending from said main line of piping, one of said pair of auxiliary lines of piping being fitted with a fluid-operated signal, a normally closed valve in said line of piping, means for actuating said valve, a normally inflated diaphragm-control connected with and located in said main line of piping intermediate of 80 said pairs of auxiliary lines of piping, the diaphragm of said control being subject to 85 pressure only upon one side thereof, and upon its other side supporting said valve-actuating means, a normally closed valve in the other auxiliary line of piping, and means for operating and opening said last-mentioned valve for deflating said diaphragm-control and releasing said valve-actuating 90 means to admit fluid into and through said fluid-operated signal.

7. A fire or signaling alarm comprising a 95 reservoir or tank, adapted to receive a fluid, a fluid-compressor, a line of piping leading from said compressor to said reservoir or tank, a pair of lines of piping in communication with said reservoir or tank, one of 100 said pair of lines of piping being fitted with a fluid-operated signal, a normally closed valve in said line of piping, a balance lever connected with said valve, a normally inflated diaphragm-control connected with and located intermediate of said pairs of lines of 105 piping, means in the other line of said pair of lines of piping for deflating said diaphragm-control, and means actuated by said diaphragm-control for releasing said lever 110 and opening the valve in the first-mentioned line of piping of said pair of lines of piping to admit the fluid into and through said 115 fluid-operated signal, consisting of a pivoted bell-crank balanced upon said diaphragm-control, a holding member normally in retaining engagement with said bell-crank, and a flexible connection between said holding member and said first-mentioned balanced lever.

8. A fire or signaling alarm comprising a 120 reservoir or tank, adapted to receive a fluid, a fluid-compressor, a line of piping leading from said compressor to said reservoir or tank, a pair of lines of piping in communication with said reservoir or tank, one of 125 said pair of lines of piping being fitted with a fluid-operated signal, a normally closed valve in said line of piping, a balance lever connected with said valve, a normally in- 130

flated diaphragm-control connected with and located intermediate of said pairs of lines of piping, a normally closed valve in the other line of said pair of lines of piping, means for operating and opening said last-mentioned valve for deflating said diaphragm-control, and means actuated by said diaphragm-control for releasing said lever and opening the valve in the first-mentioned line of piping of said pair of lines of piping to admit the fluid into and through said fluid-operated signal, consisting of a pivoted bell-crank balanced upon said diaphragm-control, a holding member normally in retaining engagement with said bell-crank, and a flexible connection between said holding member and said first-mentioned balanced lever.

9. In a fire or signaling system, a line of piping containing a fluid-operated signal, and a normally closed valve in said line of piping, means for opening said valve, combined with means in which the fluid is maintained under compression and with which said line of piping is connected, and a dia-

phragm-device adapted to be actuated by the fluid-pressure, said device having an inlet and a release-opening, said inlet being of smaller area than said release-opening.

10. In a fire or signaling system, a line of piping containing a fluid-operated signal, and a normally closed valve in said line of piping, means for opening said valve, combined with means in which the fluid is maintained under compression and with which said line of piping is connected, a diaphragm-device adapted to be actuated by the fluid-pressure, and a pipe leading from said first-mentioned line of piping and connected with the inlet of said diaphragm-device, and a perforated plug within said pipe located near said inlet to provide an inlet of smaller area than said release-opening.

In testimony, that I claim the invention set forth above I have hereunto set my hand this 2nd day of December, 1915.

JAMES M. SEYMOUR, Jr.
